CLAIM

The ornamental design for an offset oil rack stand, as shown and described.

DESCRIPTION

FIG. 1 is an oblique view of an offset oil rack stand according to the present application.

FIG. 2 is a front view of the offset oil rack stand of FIG. 1.

FIG. 3 is a rear view of the offset oil rack stand of FIG. 1.

FIG. 4 is a right view of the offset oil rack stand of FIG. 1.

FIG. 5 is a left view of the offset oil rack stand of FIG. 1.

FIG. 6 is a top view of the offset oil rack stand of FIG. 1; and,

FIG. 7 is a bottom view of the offset oil rack stand of FIG. 1.

The broken lines are included for the purpose of illustrating environmental structure and form no part of the claimed design.
